No. 36,806.

Patented February 16, 1904.

UNITED STATES PATENT OFFICE.

HARMON S. PALMER, OF WASHINGTON, DISTRICT OF COLUMBIA.

DESIGN FOR AN ARTIFICIAL BUILDING-BLOCK.

SPECIFICATION forming part of Design No. 36,806, dated February 16, 1904.

Application filed January 23, 1904. Serial No. 190,407. Term of patent 7 years.

To all whom it may concern:

Be it known that I, HARMON S. PALMER, a citizen of the United States, residing at No. 1450 Binney street northwest, in the city of Washington, District of Columbia, have invented a new, original, and ornamental Design for Artificial Building-Blocks, as disclosed by the accompanying drawings, made a part of this specification, of which the following is a description.

Figure 1 is a front view of the block, and Fig. 2 is a side view.

Having thus disclosed my invention, what I claim, and desire to secure by Letters Patent, is—

The ornamental design for an artificial building-block substantially as herein shown.

In testimony whereof I affix my signature in presence of two witnesses.

HARMON S. PALMER.
